[57] **CLAIM**

The ornamental design for a bottle rack, as shown and described.

DESCRIPTION

FIG. 1 is a perspective view of a bottle rack showing our new design;

FIG. 2 is a side elevational view thereof, the opposite side view being a mirror image of the view of FIG. 2;

FIG. 3 is a front elevational view thereof;

FIG. 4 is a top plan view thereof;

FIG. 5 is a rear elevational view thereof; and,

FIG. 6 is a bottom plan view of my bottle rack.
